(57) **CLAIM**

The ornamental design for a high pressure rotary nozzle, as shown and described herein.

DESCRIPTION

FIG. 1 is a front perspective view of my new nozzle design. Portions shown in dashed lines form no part of my new design.

FIG. 2 is a rear perspective view of my new nozzle design.

FIG. 3 is a right side view of my new nozzle design.

FIG. 4 is a left side view of my new nozzle design.

FIG. 5 is a top view of my new nozzle design.

FIG. 6 is a bottom view of my new nozzle design.

FIG. 7 is a front view of my new nozzle design. Portions shown in dashed lines form no part of my new design; and, FIG. 8 is a rear view of my new nozzle design. Portions shown in dashed lines form no part of my new design.

The broken lines shown represent portions of a high pressure rotary nozzle and form no part of the claimed design.
